UNITED STATES PATENT OFFICE.

ALLEN E. OSTRANDER, OF PATERSON, NEW JERSEY, ASSIGNOR TO
AMERICAN CAR & FOUNDRY COMPANY, OF ST. LOUIS, MISSOURI,
A CORPORATION OF NEW JERSEY.

HOPPER-BOTTOM GONDOLA CAR.

No. 840,798.

Specification of Letters Patent.

Patented Jan. 8, 1907.

Application filed June 29, 1906. Serial No. 324,034.

To all whom it may concern:

Be it known that I, ALLEN E. OSTRANDER, a citizen of the United States, residing at Paterson, New Jersey, have invented a certain 5 new and useful Improvement in Hopper-Bottom Gondola Cars, of which the following is a full, clear, and exact description, such as will enable others skilled in the art to which it appertains to make and use the same, reference 10 being had to the accompanying drawings, forming part of this specification, in which—

Figure 1 is a plan view of the hoppers of a gondola car constructed in accordance with my invention. Fig. 2 is a view the right-hand side of which is an elevation of the side of the car and the left-hand side of which is a longitudinal section; and Fig. 3 is a transverse sectional view taken on the line 3 3 of Fig. 1.

20 This invention relates to cars, and particularly to hopper-bottom gondola cars.

The object of my invention is to provide a steel car possessing maximum strength with minimum weight and in which the hoppers 25 are formed in a novel manner.

Referring to the drawings, which represent the preferred form of my invention, 1 designates the center sills of the car; 2, the plate-girder sides, provided at their lower edges

30 with angles 3, and 4 designates pressed-metal channel-shaped members which form the cross-bearers and are connected to the center sills and to the plate-girder sides. Gusset-plates 5, each provided with a pressed flange

35 6, are connected to the plate-girder sides and to one of the flanges of a pressed-metal side stake 7, said gusset-plates extending below the floor of the car and being connected to the webs of the cross-bearers 4 by rivets 8.

40 A strengthening-angle 9, extending from the upper edge of the plate-girder side to the floor of the car, is connected to each gusset-plate 5, to the plate-girder side, and to the other flange of the side stake 7.

45 The floor-plates 10 of the car are connected by rivets 11 to the upper flanges of the cross-bearers 4, and the center floor-plate 12, which extends between the twin hoppers, is connected to the upper flanges of the center sills, as 50 shown in Fig. 1. As the hoppers are of the

same construction, I will describe only one of them.

The center sheet of the hopper is composed of two plates 13 and 13, (shown in Figs. 1 and 2,) which are flanged at their upper ends and 55 connected to the upper flange of the cross-bearer by the same row of rivets 11 which connect the floor-plates to the cross-bearer, the floor-plates being lapped over the flanges of said plates 13, as shown in Fig. 2. The 60 outside sheet of the hopper consists of a central plate 14 and two end plates 15, connected by rivets 16, the end plates being also connected by rivets 17 to the plates 13, which 65 form the center sheet of the hopper. These 70 end plates 15 are of pressed metal and are so constructed that they form the outside corners of the hopper, one half of each plate lying in the plane of the central plate 14 and the other half lying in the plane of the plate 75 13. The central plate 14 inclines inwardly toward the center of the car, as shown in Fig. 3, to provide for the required clearance and is provided with a flange 18, through which rivets pass to connect said plate to the side of 80 the car. On a narrow car, however, the plate 14 need not be inclined inwardly. The end plates 15 are also provided with upwardly-projecting flanges, through which rivets pass to connect said plates to the angle 3, at the 85 lower edge of the plate-girder side, and the ends of said plates 15 are flanged upwardly at 19 and are connected to the gusset-plates 5, the strengthening-angles 9, which aid in securing said gusset-plates to the sides of the 90 car, being bent slightly, as shown in Fig. 2, to provide a space for the flange 19 of plates 15.

The inside sheet of the hopper is formed by one of the center sills and a plate 20, provided with a flange through which rivets 21 pass to connect it to the lower flange of the center sill, as shown in Figs. 2 and 3, angles 22 being connected to the center sill to extend beneath and support the inner edges to the center-sheet plates 13, which are connected to said angles by rivets 23.

The doors 24 of the hopper slope toward the center of the hopper when closed, thus making the application of the door-operating device easier and also providing a sufficient 100

clearance for the doors when they are open. Each door has connected thereto two stiffening-angles 25, placed back to back along the lower edge of the door, and hinges are preferably used for connecting said doors to the center-sheet plates 13, the fixed members 26 of the hinges being preferably of cast or malleable iron and connected to flanges 13^a on said plates and the movable members 27 being preferably of wrought-iron and connected to the doors and extending from the top to the bottom edges of the doors, as shown in Fig. 2. To afford a bearing for the doors when they are closed, angles 28 are connected to the central plate 14 of the hopper and to the plate 20, which forms the inside sheet of the hopper.

Having thus described my invention, what I claim as new, and desire to secure by Letters Patent, is—

1. A car comprising sides, cross-bearers, gusset-plates connected to the sides and to the cross-bearers, inclined plates connected at their upper ends to the cross-bearers and forming the center sheet of a hopper, a central plate connected to the side of the car and forming part of the side sheet of the hopper, said plate being inclined inwardly, and end plates connected to said central plate, to the inclined plates, to the gusset-plates, and to the sides of the car; substantially as described.

2. A car comprising center sills, cross-bearers, inclined plates connected to the cross-bearers and forming the center sheet of a hopper, means for connecting said plates to the center sill, inclined doors connected to the inner ends of said plates, and a plate connected to the center sill between the inner ends of said inclined plates and projecting below said plates to form the inside sheet of the hopper; substantially as described.

3. In a hopper-bottom car, center sills, inclined plates forming the center sheet of the hopper, and supporting-angles connected to the center sill and extending underneath the inner edges of said plates; substantially as described.

4. In a hopper-bottom car, inclined plates forming the center sheet of the hopper, doors connected to the lower edges of the center-sheet plates, outside and inside sheets having portions which extend below the lower edges of said inclined plates, and members connected to the inside and outside sheets below the inclined center-sheet plates to act as bearings for said doors when they are closed; substantially as described.

5. In a hopper-bottom car provided with channel-shaped center sills and plate-girder sides, plates depending from the center sills and provided with flanges which rest upon and are riveted to the lower flanges of the

center sills, said plates acting as the inside sheets of the hoppers, inwardly-inclined plates forming the outside sheets of the hopper and provided with flanges which are connected to the plate-girder sides, plates forming the center sheets of the hopper and being connected to the center sills and to said inwardly-inclined plates, and doors connected to said center-sheet plates; substantially as described.

6. A car comprising a side, a cross-bearer, a gusset-plate connected to said side and extending below the floor of the car and connected to the cross-bearer, a strengthening-angle connected to the gusset-plate and to the side, an inclined plate forming the center sheet of a hopper and being connected to said cross-bearer, and a plate connected to said plate and to the side of the car and provided with a flange which is connected to the gusset-plate and to the strengthening-angle; substantially as described.

7. A car comprising center sills, plate-girder sides, flanged members connected to the sills and to the sides to form a cross-bearer, gusset-plates connected to the sides and to the webs of the cross-bearers below the floor of the car, hoppers arranged on each side of the center sills and comprising inclined plates provided with flanges which are connected to the cross-bearers, the sides and the center sills, and doors for said hoppers; substantially as described.

8. A car having a hopper in which the corners are formed by sheet-metal plates that are separate from the side and end sheets of the hopper; substantially as described.

9. A car having a hopper consisting of side sheets and end sheets and separate sheet-metal plates forming the corners of the hopper; substantially as described.

10. A car provided with a hopper in which the side sheets and end sheets have parallel edges and separate sheet-metal plates connected to the side and end sheets to form the corners of the hopper; substantially as described.

11. A car having a hopper consisting of side sheets and end sheets, and pressed-metal plates connected to said side and end sheets and forming the corners of the hopper; substantially as described.

12. A gondola car consisting of sides, transversely-extending cross-bearers or floor-beams, a hopper located between said cross-bearers, and gusset-plates arranged at the outside corners of said hopper and being connected to the sides and to the cross-bearers; substantially as described.

13. A car comprising sides, cross-bearers, a hopper located between said cross-bearers, gusset-plates arranged at the outside corners of said hopper and being connected to the

sides and to the cross-bearers, and side stakes connected to said gusset-plates and to the cross-bearers; substantially as described.

14. A car comprising a side, a cross-bearer, 5 an end sheet of a hopper connected to said cross-bearer, and a gusset-plate connected to the side and to the cross-bearer; substantially as described.

In testimony whereof I hereunto affix my signature, in the presence of two witnesses, to this 20th day of June, 1906.

ALLEN E. OSTRANDER.
